(57) **CLAIM**

The ornamental design for a handheld device, as shown and described.

DESCRIPTION

FIG. 1 is a front elevational view of a handheld device depicting our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

The broken line shown in the upper area of FIGS. 1 and 7 represents an unclaimed area up to but not including the circular member illustrated by the solid line and forms no part thereof. The other broken lines on the front and rear surfaces define the bounds of the claimed design and form no part thereof. All other broken lines are for the purpose of illustrating portions of the handheld device and form no part of the claimed design.
